UNITED STATES PATENT OFFICE.

LINCOLN MOSS, OF NEW YORK, N. Y., ASSIGNOR TO ROBINS CONVEYING BELT COMPANY, OF NEW YORK, N. Y., A CORPORATION OF NEW JERSEY.

HOISTING APPARATUS.

No. 849,257.

Specification of Letters Patent.

Patented April 2, 1907.

Application filed June 29, 1904. Serial No. 214,622.

To all whom it may concern:

Be it known that I, LINCOLN Moss, a citizen of the United States, and a resident of the borough of Manhattan, in the city, county, and State of New York, have invented certain new and useful Improvements in Hoisting Apparatus, of which the following is a specification accompanied by drawings.

10 My invention relates generally to hoisting apparatus, but has special reference to instrumentalities for raising and lowering and imparting lateral movement to clam-shell buckets and other carriers, and it includes 15 novel devices for so opening, closing, and moving clam-shell buckets.

The principal object of the invention is to produce a novel and efficient hoisting apparatus in which the working forces are so 20 counterbalanced that no tendency to run away is imparted to a horizontally-movable carriage or truck, in which means are provided for maintaining the bucket or other carrier at a constant height while moving 25 laterally, and in which the reeving of the operating-ropes is such that the standing parts do not move inward with the carrier, so making it possible to use a boom for the carrier-supporting truck having side trusses 30 connected by braces over the tops of the trusses.

A further object of the invention is to reduce the amount of rope to be wound under strain in the operation of the apparatus, so 35 lessening the expenditure of power and decreasing the required capacity of the winding-drums or other sources of power.

Several different forms of apparatus, all embodying the invention, are hereinafter 40 described and are illustrated in the accompanying drawings, in which corresponding parts in the several figures are identified by similar characters of reference throughout.

In the drawings, Figure 1 is a perspective view of a hoisting-tower constructed according to the present invention. Fig. 2 is a diagrammatic view showing the application of the invention to a flying bridge. Fig. 3 is a diagrammatic view showing another way of applying the invention to a flying bridge; Figs. 4, 5, and 6, diagrams showing separately the ways of reeving the bucket-closing cable, the bucket-dumping cable, and the truck-traversing cable. Fig. 7 is a diagram show-

ing the arrangement of the bucket closing 55 and dumping cables with two barrel-sheaves. Fig. 8 is a view of a barrel-sheave for the production of differential effects. Fig. 9 is a diagrammatic view showing the application of the invention to a crane of the mast and boom type.

Referring to the drawings, and more particularly to Figs. 1, 4, 5, and 6, 1 designates a tower which may be of any preferred construction. The tower is shown as comprising a plurality of upwardly - converging members 2 2 2 2, mounted upon base-timbers 3 3 3 3. A boom or runway 4 is supported by the tower 1 at a suitable height, its outer end being sustained by guys 17 17, and this boom or runway is preferably formed of two side members spaced and braced apart to form a track for a carriage or truck 5, provided preferably with wheels 6, mounted upon axles 7 near the 75 ends of the carriage or truck. The carriage or truck may be moved inward and outward upon the boom or runway by any suitable devices for that purpose; but for purposes of illustration I have shown a winding-engine 8 at the base of the tower and a traversing cable 9 attached at its ends to the ends of the carriage or truck and passing over guide sheaves or pulleys 10 11 12. Intermediate of its ends the traversing cable passes several 85 times around the drum of the engine 8, and it is obvious that by turning the drum in one direction or the other as desired the carriage or truck may be moved inward or outward along its track. 90

Between its axles the carriage or truck 5 is provided with a rotatable drum or barrel-sheave 13. The "barrel-sheave," as I prefer to call it, has attached thereto in the middle one end of the closing rope or cable 14 95 of a clam-shell or grab bucket 15. Near the ends of the barrel-sheave the ends of a rope or cable 16 for operating the barrel-sheave are attached. Both ends of the operating-rope are wound around the barrel-sheave in 100 the same direction; but from one end the rope extends forward from the bottom of the barrel-sheave and from the other end the rope extends rearward from the top of the barrel-sheave. The rope 16 is rove around 105 guide sheaves or pulleys 18 19 at the respective ends of the boom and around pulleys 20 21 in the top of the tower 1. In the bight

of the rope 16 a traveling sheave 22 is carried. A rope 23 extends from the traveling sheave to an apparatus for applying power thereto, such as the drum 24 of a winding-engine 25.

The dumping-rope 26 of the bucket 15 is shown attached at both ends to the bucket-hanger and having the two leads thereof passing upward over guide-pulleys 27 28 on the carriage 5 and thence around pulleys 29 30 at the respective ends of the boom and pulleys 31 32 at the top of the tower. In the bight of the rope 26 a traveling sheave 33 is carried, from which a rope or cable 34 extends to the drum 37 of the engine 25.

The operation of the apparatus above described may be easily understood from the drawings. The carriage being at the outer end of the boom or runway and the bucket lowered into the barge 35 or other load-container, the winding of the rope 23 upon the drum 24 will draw the sheave 22 downward, so causing the unwinding of the rope 16 from the barrel-sheave and at the same time causing the winding thereon of the rope 14, which closes and elevates the bucket 15. When the bucket reaches the desired elevation, the winding of rope 23 is stopped and the carriage 5 is moved inward to bring the bucket over the hopper 36. During the inward movement of the carriage the barrel-sheave is stationary upon its axis and the rope 16 runs freely over its guide-pulleys and around the sheave 22. During the closing and hoisting of the bucket the rope 34 is wound upon the drum 37, drawing the sheave 33 downward and maintaining some tension upon the dumping-rope 26 in order to relieve the rope 14 of a portion of the strain due to the weight of the bucket 15 and its load. When the slack is taken up and the pull upon the rope 26 is transmitted to the bucket-hanger by slackening the cable 23 on drum 24, the bucket-sections will be separated and the load dumped. The carriage will then be moved outward to the end of the boom and the bucket lowered, with the sections spread apart, by simultaneously allowing the ropes 23 and 34 to unwind from drums 24 and 37.

During the outward movement of the carriage both the bucket closing and dumping cables will run freely over the guide-pulleys therefor and through the traveling sheaves 22 and 33.

In the operation of the apparatus as above described the length of cable which is wound under tension is unusually small for an apparatus in which the operating cables or ropes are so arranged that the strains upon the carriage are balanced. By substituting for the winding-engine 25 other apparatus for drawing the sheaves 22 and 33 downward—such, for example, as that disclosed in my co-pending application, Serial No. 191,925, filed

eliminated except the winding of the rope 14 upon the barrel-sheave.

In the apparatus illustrated in Fig. 1 the sections of the barrel-sheave upon which the several leads of rope are wound are of the same diameter, and the rate at which the leads of the operating-rope are wound is the same as the rate at which the bucket-closing rope is unwound at the same time. If, however, different rates of winding and unwinding are desired in these ropes, the barrel-sheave may be made with portions having different diameters. Such a barrel-sheave 38 is shown in Fig. 8. In Fig. 8 sheaves 39 for two bucket-closing ropes are shown, the two ropes being parallel and serving to hold the closing-roll of the bucket parallel to the barrel-sheave. The ends of the operating-rope are attached to the middle portion of the barrel-sheave 38 and wound thereon in opposite directions. As a result of this construction rapid shifting is effected at the expense of power. By employing a single bucket-closing rope attached to the middle portion of the barrel-sheave and attaching the ends of the operating-rope to the two sheaves 39 a more powerful shift may obviously be obtained at the expense of speed.

The application of the invention to flying bridges is illustrated in Figs. 2 and 3, in which two slightly-different arrangements of the elements of the invention are shown. The structures are illustrated diagrammatically only in these figures, as the details of construction may be varied indefinitely without departing from the spirit of the invention if the general arrangement of parts is left unchanged.

Referring to Fig. 2, 40 designates a flying bridge of any approved construction and provided with a track 41 for the carriage 42, which is similar in all respects to the carriage above described. The carriage-traversing cable or rope 43 is rove in the same manner that the cable 9 is rove in the apparatus already described and is operated by a suitable winding-engine; but any other devices of suitable character may be employed instead. The operating-rope 44 for the barrel-sheave 45, to which the bucket-closing rope is attached in the manner already explained, presents forwardly and rearwardly extending leads, the former passing around a guide-pulley 46 at the front end of the track and then around a smaller pulley 47 near the rear end of the track, while the latter lead passes rearward and downward over a pulley 48 adjacent to the pulley 47. The bight of the rope 44 hangs downward and carries a traveling sheave provided with means for drawing it downward, as in the apparatus first described. The bucket-dumping rope 49 has the two leads thereof rove over pulleys 50 51 on the carriage, and from the carriage the front lead extends forward around the pulley 52

and then rearward and downward over the pulley 53. The back lead of the rope 49 passes directly rearward and downward over a pulley 54, and in the pendent bight of the rope 49 a traveling sheave, provided with means for drawing it downward, is suspended.

The apparatus shown in Fig. 3 is designed to meet conditions under which it is desirable that the bights of the operating-rope and the bucket-closing rope be disposed horizontally, and this apparatus shows the use of a barrel-sheave for drawing the bucket-dumping rope upward. In this form of apparatus the bridge 55 presents a track 56 for the carriage 57, and supplemental tracks 58, 59 are provided above the main track. The carriage 57 is provided with two barrel-sheaves 60, 61, to which are attached operating-ropes 62 and 63, respectively. From the sheave 60 a bucket-closing rope extends to the bucket and a bucket-dumping rope extends from the sheaves 61 to the bucket. The front lead of the operating-rope 62 passes around a guide-pulley 64 at the front end of the bridge, and then upward over a pulley 65, and the back lead extends rearward, around a pulley 66, then forward again around a pulley 67, and upward over a pulley 68. The bight of the rope 62 extends rearward, and a traveling sheave, carried by a small truck 69, is disposed therein. This truck is movable along the track 58, and the rope extends rearward from the truck and downward over a guide-pulley to suitable winding mechanism. The operating-rope 63, attached to the barrel-sheave 61, has the forward lead thereof carried forward around a guide-pulley 71 and then upward and around another guide-pulley 72. The back lead of the rope 63 is rove around guide-pulleys 73 and 74 near the rear end of the bridge and is then carried forward around a guide-pulley 75, then upward and around a guide-pulley 76. The bight of the rope 63 is engaged by a traveling sheave carried by a small truck 70 movable along the track 69, and a rope from this truck extends rearward and downward over a guide-pulley to suitable winding mechanism. The devices for traversing the truck or carriage 57 are shown as substantially the same as those shown in Fig. 2.

The application of the invention to a crane of the ordinary mast and boom type is shown in Fig. 9. In this figure a truck or carriage 77 is shown as mounted to travel on the boom of the crane. The truck or carriage 77 is provided with a barrel-sheave 78, from which a load-supporting rope hangs downward, as in the forms of apparatus already described. The operating-rope 79 for the barrel-sheave has the forward lead thereof rove around a guide-pulley 80 at the outer end of the boom and is then carried backward and around a similar guide-pulley 81 upon the mast of the crane. The back lead

of the rope 79 extends rearward from the drum and passes around a guide-pulley 82. The bight of the rope 79 is pendent from the guide-pulleys 81 and 82, and in the bight a traveling sheave is carried. Any suitable device may be attached to the traveling sheave to draw it downward.

The operation of the several forms of apparatus illustrated in Figs. 2, 3, and 9 is so clearly obvious from the drawings and so closely analogous to the operation of the form of apparatus first described that specific description thereof is regarded as unnecessary.

While I have described and illustrated several slightly different embodiments of my invention, it is to be understood that the invention may be embodied in structures differing from those described in various details of construction. I do not, therefore, limit myself to the exact structures disclosed, but reserve the right to make changes therein within the scope of the invention, which is clearly defined in the claims.

Having thus described my invention, what I claim, and desire to secure by Letters Patent, is—

1. In hoisting apparatus, the combination with a barrel-sheave or drum of a load-supporting rope attached to the barrel-sheave or drum, and an operating rope or cable having both ends attached to said barrel-sheave or drum and both leads wound thereon in the same direction but extending from the barrel-sheave or drum in opposite directions.

2. In hoisting apparatus, a barrel-sheave or drum, a flexible load-supporting member attached to the barrel-sheave or drum, a flexible operating member having both ends attached to the barrel-sheave or drum and wound thereon in the same direction but extending therefrom in opposite directions, and means engaging the bight of said flexible operating member to exert a pull thereon.

3. In hoisting apparatus, a barrel-sheave or drum, a flexible load-supporting member attached to said drum, a flexible operating member attached at both ends to said drum and having both leads wound thereon in the same direction but extending therefrom in substantially opposite directions, spaced guides for the leads of said operating member, and means in the bight of said operating member for simultaneously placing both leads under tension.

4. In hoisting apparatus, a barrel-sheave or drum, a load-supporting rope or cable attached to said barrel-sheave or drum, an operating rope or cable having both ends attached to said barrel-sheave or drum and wound thereon in the same direction but extending therefrom in substantially opposite directions, spaced pulleys for the leads of said operating rope or cable and means engaging the bight of said operating rope or

cable for placing both leads thereof under equal tension.

5. In hoisting apparatus, a barrel-sheave or drum, a flexible load-supporting member attached to the drum, an operating rope or cable having both ends attached to the drum and having both leads wound on the drum in the same direction but extending therefrom in opposite directions, guide-pulleys over 10 which said leads pass and a traveling sheave disposed in the bight of said operating rope or cable to exert a pull thereon.

6. In hoisting apparatus, a barrel-sheave or drum, movable bodily, a load-supporting 15 rope or cable attached to said drum, and an operating rope or cable having both ends attached to the drum and wound thereon in the same direction but extending therefrom in substantially opposite directions.

20 7. In hoisting apparatus, a barrel-sheave or drum, a load-supporting rope or cable attached to said drum, means for imparting bodily movement to said barrel-sheave or drum, and an operating rope or cable having 25 both ends attached to the drum and wound thereon in the same direction but extending therefrom in substantially opposite directions.

8. In hoisting apparatus, a barrel-sheave 30 or drum, a load-supporting rope or cable

pendent therefrom, a self-filling bucket carried by said cable, a truck upon which said barrel-sheave or drum is supported, an operating rope or cable having both ends wound on said drum in the same direction but extending therefrom in substantially opposite directions, and a bucket-dumping rope or cable attached to said bucket and extending upward to the truck. 35

9. In hoisting apparatus, two barrel-sheaves or drums, a self-filling bucket, a rope or cable attached to one of said barrel-sheaves or drums and also attached to the closing-roller of said bucket, a rope or cable attached to the other barrel-sheave or drum 40 and also attached to the frame of said bucket and an operating rope or cable for each of said barrel-sheaves or drums, said operating-ropes each having both ends attached to one of said barrel-sheaves or drums but extending 45 in substantially opposite directions. 50

In testimony whereof I have signed this specification in the presence of two subscribing witnesses.

LINCOLN MOSS.
